(57) **CLAIM**

The ornamental design for clips for a handgun holster, as shown and described.

DESCRIPTION

A portion of the disclosure of this patent document contains material which is subject to copyright protection. The copyright owner has no objection to the facsimile reproduction by anyone of the patent disclosure, as it appears in the Patent and Trademark Office patent files or records, but otherwise reserves all copyright rights whatsoever. Copyright 2018. FIG. 1 is a rear perspective view of clips for a handgun holster showing the new design.

FIG. 2 is an inner front elevation view of the left clip.

FIG. 3 is an outer front elevation view thereof.

FIG. 4 is a side elevation view thereof; and,

FIG. 5 is an opposite side elevation view thereof.

The broken lines in FIG. 1 show a handgun holster that is not part of the claimed design.
